Patented Dec. 2, 1919.

UNITED STATES PATENT OFFICE.

CHARLES S. KENDRICK AND ARTHUR T. CURRY, OF DAYTON, OHIO.

GAS-BURNER.

1,323,773.

Specification of Letters Patent. Patented Dec. 2, 1919.

Application filed March 16, 1918, Serial No. 222,822. Renewed April 23, 1919. Serial No. 292,244.

To all whom it may concern:

Be it known that we, CHARLES S. KENDRICK and ARTHUR T. CURRY, citizens of the United States, residing at Dayton, in the county of Montgomery and State of Ohio, have invented certain new and useful Improvements in Gas-Burners, of which the following is a specification.

Our invention relates to new and useful improvements in gas burners such as are used for heating and cooking purposes. The object of the said improvements is to provide a gas burner of maximum efficiency which is attainable through the particular construction of the burner parts. This particular construction is aimed at the avoidance of any obstructing surfaces that might offer any resistance to an easy flow of the gas. The construction has further in view an easy cleaning of the burner all of which will be more fully described in connection with the accompanying drawings. Of said drawings Figure 1 is a top plan view of our improved burner. Fig. 2 is a side elevation showing the gas feed pipe and the mixer connected. Fig. 3 is a sectional view on the line 3—3 of Fig. 1 and Fig. 4 is a detail section showing a portion of the burner feed pipe, and the mixer as well as the service pipe which feeds the mixer.

In a detail description of our invention similar reference characters indicate corresponding parts as they appear in the drawings.

The center piece or head 1 of the burner has its interior surface rounded as at 9 to provide the least possible resistance to the passage of gas which enters the bottom of said head. The head has five screw-threaded apertures. The screw-threaded aperture 16 in the lower side of said head receives the short inlet pipe 8 which through a curved fitting 10 connects with the burner feed pipe

11. The remaining screw-threaded openings 17 are horizontal and connected therein are four hollow burner arms 2. The top side of the head has two exit burner slots 4 which

cross and provide the center of the burner with the proper gas exits. The arms 2 have for a portion of their lengths a series of 50 straight cross slots 5 and another series of slanting slots 6 which taper outwardly and spread the flame outwardly toward the ends of the burner arms 2. The ends of said arms 2 are closed with caps 3 which are screwed 55 thereon and in these caps there are outwardly tapered gas slots 7. The caps 3 are detachable in order to clean the burner arms when necessary, and the arms themselves are detachable in order to clean body of the 60 burner when necessary. The gas enters the body of the burner in proper mixture. It has been found by experience that the mixer should be located some distance from the burner, therefore, the feed pipe 11 is of a 65 suitable length to enable this accomplishment. The mixer 12, which is of flaring form, is secured to the entrance end of the feed pipe 11. Into the mixer the gas is discharged immediately from the service pipe 70 15 and nozzle 13, an intervening valve 14 controlling the passage.

Having described our invention we claim:

A burner of the type specified comprising a head having a series of screw-threaded 75 apertures, the upper surface thereof being of rounded form and provided with cross gas exit slots, a feed pipe connected with the lowermost one of said screw-threaded apertures, a series of radial burner arms connected with the other of said screw-threaded apertures, said burner arms having for a portion of their length a series of straight transverse gas exit slots and for another portion of their length a series of transverse 80 85 outwardly tapering gas exit slots, and detachable caps inclosing the ends of said burner arms, said caps having outwardly tapering transverse gas slots therein, substantially as described.

In testimony whereof we affix our signatures.

CHARLES S. KENDRICK.
ARTHUR T. CURRY.
